UNITED STATES PATENT OFFICE.

CHARLES C. BARTON, OF NEW YORK, AND JOHN THOMSON, OF BROOKLYN, N.Y.

COMBINED PISTON AND DIAPHRAGM METER.

SPECIFICATION forming part of Letters Patent No. 313,153, dated March 3, 1885.

Application filed April 26, 1884. (No model.)

To all whom it may concern:

Be it known that we, CHARLES C. BARTON and JOHN THOMSON, citizens of the United States, residing, respectively, in the city, 5 county, and State of New York, and Brooklyn, county of Kings and State of New York, have invented certain new and useful Improvements in Fluid-Meters, of which the following is a specification.

10 Our invention relates to fluid-meters of that class in which the displacement is obtained by the combination of a piston and diaphragm and a valve system.

15 The chief objects of this invention are, first, to improve the operation and mechanical construction of fluid-measuring instruments, and, second, to reduce the cost of their manufacture.

20 To this end our invention refers particularly to the following features: first, the adaptation of the valve-actuating apparatus, the valve, piston-rod, and register-actuating apparatus to a single separate "form" or base, which, when entirely completed and assembled, is 25 placed and secured within the cylinder much as a watch or clock movement is placed within its case; second, in an improved arrangement of the valve-actuating apparatus; third, in an improved construction of the valve and 30 the valve-spindle; fourth, in an improved arrangement for transmitting the sum of the strokes of the piston to the register; fifth, in an improved register-connection; sixth, in an improved form of diaphragm, and manner of 35 securing the same to the cylinder and piston, and method of assembling the component parts of the same; seventh, in an improved form and construction of the piston.

40 In the drawings, Figure 1 is an upright central cross-section of our improved meter, exposing the valve-casing and valve-actuating apparatus in front elevation. Fig. 2 is a top plan view of the valve-casing and its appurtenances. Fig. 3 is an upright end elevation 45 of the valve-casing as viewed from the right-hand side of Fig. 2. Fig. 4 is a transverse section through the valve-casing on the line C of Fig. 2. Figs. 5 and 6 are detached views of the valve. Fig. 7 is a detached side elevation 50 of the diaphragm and clamping-rings. Figs. 8 and 9 are detached views of the piston

and clamping-ring. Fig. 10 is a side and plan view of the carriage.

In the construction of instruments of this class heretofore the practice has uniformly 55 been, so far as possible, to form the valve-casing and every portion necessary to operate as a part of the main cylinder or cylinders. The objections we have found, in so far as this precedent has been followed, are that it is practically impossible to combine the highest efficiency, the best disposition of parts within the 60 smallest possible space, with the least quantity of material, and the lowest cost to construct the component parts and to assemble 65 the same. The reasons for the enumerated objections are that the work to be done is generally within a cylinder inconvenient and difficult of access, or on a cumbrous "bonnet," 70 chest, or septum, likewise inconvenient to handle. We obviate these difficulties in the following manner:

The machine-work to be done on the lower cylinder, 1, and the upper cylinder, 2, of the figure, consists of facing off the flanges, drilling the bolt-holes 3, bearing for stuffing-box 4 and binding-screws 5, and boring the taper 6. Aside from fitting the ingress and egress pipes, 75 this is the sum of the machine-work on the cylinders.

To the taper of the crown of the cylinder is 80 fitted what will be herein termed the "valve-case" 7, in which is formed a complete system of sluices or water-ways connecting with corresponding water-ways in the cylinder, and to 85 which every working part of the meter is attached or connected. All of the operations upon the valve-casing, however, are performed before it is secured within the cylinder, its attachment thereto being effected as to position by the register-shaft 8, and as to retention 90 by the screws 5. It will be observed that these screws also serve to force the two tapering bearing-surfaces 6 of the valve-casing and cylinder together with great intimacy, thus making a 95 fluid-tight joint between them. The position of the register-shaft bearing is such that it so locates the valve-casing that the egress-sludge 9, Fig. 2, meets a corresponding cored water-way, and the ingress-sludge 10 and intermediate 100 sludge, 11, also meet corresponding water-ways in the opposite side of the cylinder. The

intermediate water-way, 12, (dotted lines, Fig. 1,) of the upper cylinder follows down and meets a corresponding water-way, 13, in the lower cylinder, thus completing the circuit. The 5 diaphragm 14 is secured between the flanges of the cylinders and to the piston 15, (in a manner to be hereinafter described,) thus forming two compartments within the cylinder—an upper, 16, and a lower, 17. The valve is of the 10 compound puppet type, and is balanced as to hydrostatic and working pressure, by "working-pressure" being meant that due to the friction developed in operating the meter.

The passage of the fluid during the time in 15 which the valve is in the position shown in Figs. 1, 2, and 3 is as follows: first, from the ingress-slue 10 to and through the induction-port 18, (induction-port 19 and eduction-port 20 being closed by the valves 21 22,) to the intermediate sluice, 11, and water-way 12, down to lower compartment, 17, thus forcing piston and diaphragm up, as see dotted outline, and expelling the fluid from upper compartment, 16, which had previously been filled, 25 through the port 19, when the valve was in the position shown in Fig. 4, into and through eduction-port 23, to the egress-slue 24, and thence out. Meantime the piston-rod 25 will have made contact with the arm of the bell-crank 26, Fig. 3, through the medium of the pin 27, which projects through the piston-rods, and also with the register-arm 50, which connects by means of the pin 28 with the piston-rod, bringing both of said parts to their alternate position. (Indicated by center lines, Fig. 3.) In the bell-crank the effect will be to force over the spring-carriage 29, against the tension of the V toggle-springs 30, whose thrust is exerted against the thrust-block 31, to the 30 valves, thus holding the valves to their seats until the "heels" of said springs—that is, their outer bearings in the spring-carriage—will have been carried beyond their dead-center, when they will act to set the valve 35 to its reversed position. The bell-crank is permitted a certain amount of "lost motion" in order to set the springs quickly from off their dead-center. The motion of the bell-crank is limited by the impact of the pin 27 40 against the stop-shoulders 32, formed in the bearing of the piston-rod. The position of the valve as now assumed is shown in Fig. 4, when the ingress-current will flow through the now open induction-port 19 directly into the upper chamber, 16, and the fluid from the lower chamber will be forced back through the intermediate water-way of the cylinder to the intermediate sluice of the valve-chamber, through the eduction-port 20 to the egress-slue of the valve-casing, and thence out.

The use of the bell-crank permits, first, a horizontal position to the valve, and, second, a direct connection with the piston-rod and motor-springs actuating the valve.

65 The spring-carriage is attached to the bell-crank by small pivots, as 33, so that said carriage takes the entire direct thrust of the

springs and relieves the bell-crank of the friction of their thrust.

It will be understood that the angle subtended by the bell-crank in its alternate positions is not transmitted to the carriage and springs, as the pivoted connection permits the carriage to travel back and forth in a vertical line only. In this direct connection of the 70 spring-carriage to the bell-crank there is a slight error of movement, in that the arc described by the bell-crank is imparted to the carriage and tends to slightly cramp the 75 springs by alternately raising and lowering 80 their heels in their horizontal plane.

To eliminate the objection noted the springs are formed as shown in Figs. 1 and 3, their center or V portions, 30, being considerably narrower than their bearing-surfaces. The 85 effect of this is to make the springs very elastic horizontally, as well as when compressed upon themselves. Thus their heels may be lifted and lowered within the limits required without interfering with their proper action, 90 besides which long and durable bearing-surfaces are provided for the knife-edge bearings to act upon.

While the carriage might readily be made solid, it is preferably "built up" by the yokes 95 33^a and bearing-blocks 34, as in this way the blocks can be formed in long pieces, with the V-bearings 35 accurately milled, and then cut to required length, while the yokes are stamped from sheet metal. The yokes, as will be seen, also prevent the springs from shifting up or down in their bearings. The face-plates 36 are exact duplicates each of the other, and are secured to the valve-casing by the screws 38. They form the outer valve-seats, and also the bearings in which the valve-spindle 37 operates. In forming the "seats" for said face-plates, and also the valve-seats 39 40 of induction and eduction ports, as see Fig. 4, the casing is cast with 100 the annular ribs x x and chambers, and the method of finishing is as follows: A milling-tool of the exact shape required boxes the eduction and induction ports 18 20, and at the same time forms a seat for the valve and the face-plate 41 on one side of the valve-casing. The operation is repeated on the opposite side, the bore being continued until the opposing surfaces are brought to any predetermined 105 distance apart. Thus the face-plates and bearings for the valve are brought exactly central with the ports, and whatever departure there may be from exact truth in the relative vertical planes of the valve-seats and face-plates—as, say, from the right angle subtended by the longitudinal center of the valve-stem to the bearing of the bell-crank—it will not materially interfere with the free and proper action 110 of the different parts, besides which the operations are few and simple.

To reduce the fitting and cost of the valves to a minimum, and to adapt the meter for correct operation in the most severe service—as the measurement of water charged with grit

and impurities—we form a flexible built-up valve in the following manner, as see Figs. 4 and 5:

On the sleeve 42 two hubs, 43, are formed 5 the required distance apart. A portion of the ends of said sleeve are threaded to receive the binding-nuts 44, and the sleeve itself is finished to a length as much less than the distance between the inner surfaces of the hubs 10 45 of the face-plates as the full distance of the stroke of the valve. The valve-spindle is formed of regular gage wire forced tightly through the sleeve. Each movement of the valve-spindle will thus cause an alternate end 15 of the sleeve to impinge upon one or other of the inner surfaces of the hubs 45 of the face-plates. Each portion of the valve is then made up of three plain disks, the first, 46, being of leather, vulcanized rubber, or any 20 suitable analogous material, the second interposed disk, 47, being of thin spring metal, and the third, 48, a duplicate of the first. All are then clamped on the sleeve against the hub by the nut, as shown. The function of 25 the stops formed by the ends of the sleeve is now apparent—namely, to take the full force of the valve-motor springs 30 and just permit the valve to make proper contact on its seats. In the event, however, of any error in the 30 construction of the parts, or of a foreign obstruction being caught between the valve and its seats, as illustrated in Fig. 6, the full force of the motor-springs will be exerted upon the valve to bring it to a seat until finally arrested 35 in its movement by the stop; hence, in consequence of the greater power of the valve-motor springs and the flexible and elastic nature of the valve, an approximately accurate contact is effected upon the valve-seat under 40 conditions that would otherwise render the instrument very inaccurate in its measurement or totally inoperative.

To effect the registration of the strokes of meters, and thereby measure the volume of 45 liquid displaced, the usual practice heretofore has been to make direct and continuous connection, whereby each stroke or unit of displacement is transmitted to the register. The objection to this is that inasmuch as in the 50 smaller sizes of instruments it requires a number of movements to displace a cubic foot, (the unit of measurement in the United States,) and that as the register is connected by a shaft passing through a packed bearing, the friction 55 is considerable, and there is liability of leakage through the said packed bearing in consequence of the frequent movements of the shaft. We obviate these objections by transmitting to the register by means of the register-shaft the result or sum total only of the 60 movements required to make up a cubic foot, or any arbitrary volume, upon the completion of the movements required to make the sum of the displacement desired to be indicated. To this end our arrangement is as follows:

On a fixed bearing, 49, of the valve-casing

is mounted the register-arm 50, carrying a pawl, 51, and a ratchet-wheel, 52, having one or more projecting pins, 53, said pins being caused to pass in proper pitch-line to intermesh with the pin-wheel 54. The said pin-wheel is fast to the register-shaft 8, mounted in another fixed bearing, 55, of the valve-casing; hence it is apparent that by a proper relation of the number of teeth in the ratchet-wheel to the piston-strokes required to measure any arbitrary unit of volume a single pin, or any one of a number of pins 53, will be caused to engage a tooth of the pin-wheel only 80 at the termination of a series of piston-strokes, and that the pin-wheel will be thus rotated a space equal to the pitch of one of its teeth, which movement, being transmitted to the register, should indicate a full unit of displacement. In the present instance the adaptation is made with special reference to differential registers as shown and described in 85 patents of the United States, Nos. 274,674 and 285,322, dated, respectively, March 27 90 and September 18, 1883, allowed to one of the present applicants. In this register each full unit of the dial corresponds to a single tooth of the dial-carrying wheel. We therefore simply attach a pinion, as 56, to the upper and 95 outer portion of the register-shaft, which has a number of leaves corresponding to the number of teeth in the pin-wheel 54. Thus each movement of the pin-wheel equal to the pitch of its teeth or pins will rotate the pinion 100 through a space equal to the pitch of its leaves, and will thus record a complete unit and the register. Supposing, therefore, that the number of piston-strokes to a cubic foot of fluid is sixteen, the number of teeth in the 105 pin-wheel ten, and a corresponding number of leaves in the pinion, it would therefore require one hundred and sixty piston movements ($16 \times 10 = 160$) to turn the register-shaft one complete revolution.

To facilitate the attachment of the pinion to the register-shaft, we slot the end of said shaft, as at 57, to a proper depth, and insert a pin, 58, transversely through the pinion, and thereby positively drive the pinion and keep 115 it in proper position on the shaft to engage the wheels of the register.

In the diaphragm 14, Fig. 7, we have found the best results by first forming it as a frustum of a cone, the two determining points in 120 its development being the diameter of the flanges or rings of the cylinders, which gives the greater diameter, and the diameter of the piston, which gives the lesser diameter. The cone is then projected sufficiently beyond these 125 points to clamp the material to the cylinder and to the piston. Then, as an inner and outer flange is not thus formed on the material of the diaphragm, it must necessarily be crimped in at the apex and stretched out at the base, 130 the advantage of which is that the flexure of the material at the clamping-points for each stroke is one-half of what it would be were flanges formed—that is, the flexure at the

point 59 for each stroke becomes the means of the two angles subtended by the full lines and the dotted outline 60 of the diaphragm. This formation also requires less material and is 5 easier to construct.

The usual manner of securing the diaphragm to the cylinder is simply to clamp it between the flanges. We have found this objectionable, in that the diaphragm is subjected to 10 great pressure by the flange-bolts tending to crush, cut, and squeeze out the diaphragm, besides bringing it in contact with corrosive metal. We instead thereof attach the base of the diaphragm to a pair of non-corrosive metal 15 rings, 61 62, the ring 62 fitting snugly within the flange 63 of the ring 61. The diaphragm is then pinched between these rings, and the two rings, as one, are placed in a groove or recess, 64, formed in the flange of the upper 20 cylinder, said groove being of such depth that the rings and diaphragm are clamped sufficiently tight to just insure the diaphragm against withdrawal and to form a water-tight joint. The inner edges, 65, of the rings are 25 slightly rounded, and the rings project within the cylinder; hence the diaphragm rolls within the fluid, completely free from any disturbing or corrosive influence. In somewhat like manner we secure the apex of the diaphragm 30 to the piston. In this instance, however, it becomes desirable to make the piston 15 of the least possible weight and the greatest stiffness in its horizontal plane to resist buckling or diaphragmatic action. To this end the piston 35 ton (see Figs. 7, 8, and 9) is formed of light sheet metal, with a rounded outer flange, 66, a raised annulus, 67, within the flange, and between the center bearing for the piston-rod and said annulus 67 are stamped a number of 40 ribs, all of which are tangent to a common circle concentric with that of the annulus 67. It will thus be seen that in whatever direction the strain may be applied, as at the lines 68 45 69, the said tangents will present a cross-sectional resistance to the strain or strains, with obvious results. The ribs may be curved instead of straight. The clamping-ring 70, Fig. 9, is formed with a rounded flange, like the piston, and an inner raised annulus, 71, the 50 latter, however, being turned in an opposite direction to that of the annulus 67 in the piston. The reason for this is that the piston and the clamping-ring lie one within the other, and are thereby accurately centered to 55 each other, when it simply remains to secure the two together upon the diaphragm by rivets or screws and nuts, as shown, to complete the work.

The mode of setting up or assembling outer 60 clamping-rings and piston is as follows: In Fig. 7 assume the piston in dotted outline to be fixed to a jig or form of the exact shape of the inner surface of the diaphragm. Then place the diaphragm upon the form. Next 65 place the outer ring over the diaphragm, the said ring being also secured in a separate form of the exact shape of the outer surface of the

diaphragm. The piston, diaphragm, and outer ring are then virtually locked together as one part. It simply remains to drive the inner ring, 62, snugly home to its position within the flange of the outer ring, thereby stretching the diaphragm and securing it at its base. Then secure the clamping-ring 71 to the piston, as set forth, when the work is completed and the 75 forms may be withdrawn. This mode also insures uniformity of volume in manufacturing without after adjustment.

It will be observed that, in facing off the flange of the upper cylinder, a downwardly-projecting collar is formed at its outer circumference, and that the flange of the lower cylinder is turned to fit this collar. The object of this construction is twofold—first, to center the two cylinders one upon the other, 80 and, second, to prevent the packing from being blown out from between the two surfaces of the flanges. Constructed in this manner, the packing may be of any fibrous or plastic material suitable, and which obviously will 85 be insured against ejection outwardly without being pinched excessively by the flange-bolts. Of course the same results would be obtained by forming the collar on the lower cylinder. 90

Although we have illustrated the outer meter-casing as consisting of two connected cylinders, the same may be of any suitable construction, and the valve-casing supporting all the operating parts, whatever may be their character, may be secured detachably within 95 the outer casing in any suitable manner. 100

It will be obvious that the valves and casing may be differently constructed without departing from the principle of our invention relating to the support of all the working parts 105 by the detachable valve-casing, and that different arrangements of channels may be made to direct the fluid first to one chamber and then to the other.

We do not herein claim, broadly, the valves 110 shown and described, as they will form the subject-matter of another and separate application, and the omission of such claims herein is without prejudice to our rights to such inventions.

We claim—

1. The combination, with the upper compartment or casing of a fluid-meter having ingress and egress openings for the passage of the fluid, of a detachable valve-casing having 120 sluices open at their ends, and adapted to fit into said compartment and connect with said ingress and egress openings directly, the operating apparatus of the meter being secured to and detachable with said casing, substantially as described.

2. The combination, with the upper compartment or casing of a fluid-meter having side ingress and egress openings for the passage of the fluid, of a detachable valve-casing 130 having sluices open at their ends and a valve or valves operating therein, said casing having secured or connected therewith the operating parts of the meter, and adapted to fit

- into said compartment and connected with the side channels, as and for the purpose set forth.
3. A detachable valve-casing having interior and exterior ports and valves adapted to be placed in one of the cylinders or compartments of a fluid-meter, said valve-casing having secured or connected with it the operating parts of the meter, and being provided with a system of sluices open at the opposite ends 5 of the casing, arranged to connect directly with a corresponding system of water-ways, substantially as described.
4. A detachable valve-casing, upon which is secured or connected the operating mechanism of the meter, adapted to a tapered bearing within the cylinder, and clamping devices holding the casing upon said bearing, substantially as set forth.
5. The combination, with the outer casing 20 of a fluid-meter, having channels and ports and a diaphragm, of a detachable valve-casing provided with channels and ports, and an interior valve constructed to direct the fluid from the inlet alternately to opposite sides of 25 the diaphragm and from opposite sides of the diaphragm alternately to the outlet, substantially as described.
6. The combination, with the detachable valve-casing, of the valve, the face-plates forming bearings for said valve, the spring-carriage and springs mounted thereon, the bell-crank, the piston-rod, and means for operating the same, substantially as specified.
7. The combination, with the detachable 35 valve-casing, of the register-shaft, the ratchet, a system of gearing connecting the said shaft and ratchet, the register-arm carrying a pawl, the piston-rod, and means for operating the same, all of said elements being mounted upon 40 the said valve-casing within the cylinder, substantially as specified.
8. The combination, in operative position and connection, of the bell-crank, the spring-carriage, and toggle-acting V-springs, said carriage and bell-crank directly and pivotally connected, for the purpose set forth.
9. The combination, with the valve, the thrust-block and carriage, and means for operating the latter, of the toggle-acting double 50 spring, formed in the manner and for the purpose herein shown and described.
10. In a fluid-meter, the built-up spring-carriage consisting of a pair of bearing-blocks united by a pair of yokes, substantially as 55 specified and shown.
11. In a fluid-meter, the combination, with the stops and spring-motor apparatus, of a built-up puppet-valve constructed of disks of pliant packing material and an interposed 60 flexible disk of spring metal, whereby the said valve is relieved from excessive impact upon the valve-seat.
12. In a fluid-meter, the combination, with a spring-motor apparatus, of a built-up valve-spindle consisting of a sleeve the ends of 65 which form stops, a pivotal portion consisting of a wire forced through the sleeve, and clamping-nuts adapted to be screwed upon the sleeve to secure the valve, substantially as shown and set forth. 70
13. The combination, with a meter, of a registering mechanism having a packed shaft extending through the outer casing, and connections, substantially as described, between the shaft and measuring appliances, whereby 75 said shaft is normally stationary, and is moved but once to a number of movements of the measuring appliances, substantially as described.
14. In a fluid-meter, the combination, with 80 the displacing means, as the piston and diaphragm, of a system of direct-acting gear-wheels, the construction and arrangement being such that a multiple of displacements is registered as one unit upon the register by a 85 single movement of the register-shaft, which is normally stationary, substantially as specified.
15. In a fluid-meter, a pliant frustum-of-cone-shaped diaphragm connecting the piston 90 and cylinders, to the smaller end of which is attached the piston, and to the larger end of which are attached the separate clamping-rings of non-corrosive metal, substantially as shown and described. 95
16. The combination, with the upper cylinder of a fluid-meter, having a grooved bearing or recess, of the diaphragm and two separate non-corrosive rings, between which the diaphragm is clamped, and the whole, as one, 100 contained within the grooved bearing or recess in the upper cylinder, substantially as set forth.
17. The combination, with the smaller rim of the diaphragm, of the piston and an annulus riveted or screwed thereto, said piston and annulus having grooves which act to center the one upon the other, substantially as set forth. 105
18. In a fluid-meter, a piston consisting of 110 light sheet metal, having within its circumference a number of radial grooves or ribs, all of which are tangent to a common circle concentric with the circumference of the piston, substantially as shown and set forth. 115

In testimony whereof we have signed our names to this specification in the presence of two subscribing witnesses.
